UNITED STATES PATENT OFFICE

MAX SPIEGEL, OF PHILADELPHIA, PENNSYLVANIA

COMBINED DOOR BELL AND ALARM

Application filed March 21, 1930. Serial No. 437,794.

This invention relates to a combined door bell and alarm mechanism and has particular relation to a mechanism in which a common bell serves for both purposes.

5 In connection with mechanical door bell arrangements, it is desirable that the bell should not only serve to operate as a door bell upon actuation of a push button or the like but should also serve to sound a warning if 10 the door with which it is associated is opened by an intruder. It is the broad object of the present invention to provide a device of this character. More specifically 15 it is an object of the invention to provide such a device in which the mechanism may be rendered inoperative to sound the bell upon manual manipulation of the push button but in which case it will remain operative to act as an alarm.

20 Other more specific objects relating to details of construction will be apparent from the following description read in conjunction with the accompanying drawings, in which:

25 Fig. 1 is a horizontal sectional view through a door and its associated frame showing the connections of the improved mechanism;

Fig. 2 is a fragmentary elevation of the 30 same; and

Fig. 3 is a detail view partially in section showing the bell unit.

A frame 2 supports through suitable hinges in the usual manner a door 4 to the outside 35 of which is secured a push button casing 6 through which a plunger 8 is adapted to slide against the tension of a spring 10 when manually manipulated, this plunger being guided in its inner end through an opening in the door. Secured to the inner end of the plunger is a chain or other flexible connection 40 designated 12 passing in contact with either the door or a block 14 in which is pivotally mounted a spring detent member 16 which 45 may be pivoted to a position in which it does not engage the chain or to a position in which it engages a link of the chain and holds it against longitudinal movement relative to the door.

50 The chain 12 at its inner end is connected to

the pivoted rod 18 which carries at its outer end a hammer 20 arranged to cooperate with a bell 22, the inner end of this rod being carried on a spindle provided with pallets 24 cooperating with an escapement wheel 26 which is arranged to be driven by a suitable spring clockwork mechanism as is usual in bells of this type.

To render the mechanism inoperative to ring the bell, there is provided a detent 28 carried by the spindle of a rotatable member 30 projecting outside of the casing 34 enclosing the clockwork mechanism. Preferably this mechanism, its cover 34 and the bell 22 are secured to a suitable base 32, which may be attached to the door frame. There is thus formed a unit which is readily secured in proper position.

When it is desired that the mechanism should operate as a door bell, the detent 28 is located away from contact with the escapement wheel 26 and the detent 16 is pivotally moved from engagement with the chain 12. Under these conditions with the door closed the spring 10 serves to urge plunger 8 outwardly pulling the rod 18 to an extreme position so that the escapement is unable to produce oscillatory motion thereof. Under these conditions inward movement of the plunger 8 serves to produce longitudinal 75 movement of the chain 12, liberating the rod 18 so that it receives an oscillatory motion from the escapement mechanism and rings the bell.

It will be observed that when the parts are 85 in this condition opening of the door would serve to permit a longitudinal movement of the chain, freeing the rod 18. Accordingly, before the door is opened under normal conditions, the detent 28 would be engaged with 90 the escapement wheel to prevent the bell from ringing.

At times it is desirable that the door bell be prevented from operating but that the mechanism should serve as a burglar alarm. 95 To effect this result, the detent 16 is engaged with the chain by movement to the position illustrated in the figures. At the same time, of course, the detent 28 must be disengaged from the escapement wheel. It will be seen 100

now that movement of the plunger 8 inwardly will not liberate the rod 18 but the chain will be held tight between the rod 18 and the spring detent 16. On the other hand, 5 if the door be opened, a longitudinal movement is imparted to the chain 12 by reason of the fact that the part of the chain engaging the detent 16 moves toward the bell mechanism across the line on which the door is 10 hinged to the frame. It will be obvious, therefore, that there is provided a burglar alarm which will operate whether the mechanism is operative or inoperative as a door bell. Of course, the mechanism may be rendered inoperative for all purposes by the use 15 of the detent 28.

It will be obvious that numerous variations may be made from the preferred mechanism illustrated. For example, the chain 12 may 20 be replaced by any type of flexible connection and the detent 16 may take various forms. The same is true of the bell mechanism which, if desired, may be located at a remote position, the flexible connection passing 25 about suitable pulleys to confine it to a proper path. Instead of being connected directly to the hammer rod, the chain may be connected to any other portion of the mechanism which will permit it to control the sounding 30 of the bell.

What I claim and desire to protect by Letters Patent is:

1. A combined door bell and alarm mechanism including a bell, a hammer, hammer 35 actuating mechanism, a manually operable member, connections between the manually operable member and the hammer actuating mechanism whereby operation of the member causes operation of the actuating mechanism, 40 said connections being arranged whereby opening of a door in connection with which the mechanism is used serves to cause operation of the actuating mechanism, and restraining means for rendering the manually oper- 45 able member ineffective to cause operation of the actuating mechanism while the connec- tions remain operative upon opening of the door.

2. A combined door bell and alarm mecha- 50 nism including a bell unit comprising a bell, a hammer, and hammer actuating mechanism adapted to be carried by a building, a manu- ally operable member adapted to be carried by a door, connections between the member 55 and hammer actuating mechanism arranged to extend across the line upon which the door hinges, and means for securing the connec- tions to the door whereby the member may be rendered inoperative to cause operation of 60 the actuating mechanism while the connec- tions are operable to cause operation of the actuating mechanism upon opening of the door.

3. A combined door bell and alarm mecha- 65 nism including a bell unit comprising a bell,

a hammer, and hammer actuating mechanism adapted to be carried by a building, a push button carried by a door, a flexible member ar- ranged to be connected between the hammer actuating mechanism and the push button across the line upon which the door hinges whereby its longitudinal movement effected by movement of the push button causes opera- 70 tion of the hammer actuating mechanism, and means for securing the flexible member to the door between the push button and the line of hinging whereby the push button is rendered inoperative but the actuating mechanism is operated upon opening of the door.

In testimony of which invention, I have 80 hereunto set my hand, at Philadelphia, Penn- sylvania, on this 19th day of March, 1930.

MAX SPIEGEL.
